UNITED STATES PATENT OFFICE.

JOHN E. HOY, OF MIDLAND, MICHIGAN, ASSIGNOR TO THE DOW CHEMICAL COMPANY, OF MIDLAND, MICHIGAN, A CORPORATION OF MICHIGAN.

MELTING POT FOR LIGHT METALS AND ALLOYS THEREOF.

Application filed January 14, 1926. Serial No. 81,240.

The present improvements relating, as indicated, to a metal melting furnace, have more particular regard to the provision of a furnace suitable for melting light metals and alloys thereof, such as magnesium and alloys in which magnesium is the predominant constituent. It is unnecessary to note that the melting of magnesium and the handling of the molten product presents special difficulties. The object of the invention is to provide an arrangement of melting pots wherein a considerable body of the metal may be maintained in molten state without undue exposure to the atmosphere and yet such metal may be readily withdrawn for use as required in casting into molds or for other purposes.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—

The single figure there appearing is a central vertical section through a melting furnace embodying my present improved construction and arrangement of melting pot.

Referring to said drawing, the furnace, it will be seen, is built up of the usual brick walls 1 so as to provide a main chamber 2 and a supplemental chamber 3 through which the heating gases from the burner 4, or equivalent source, will pass in parallel. A melting pot 5 is set into the upper portion of said main chamber 2 and serves to close off the same save for a suitable laterally opening exit flue (or flues) 6. A second smaller pot 7 is supported in the supplemental chamber 3 below and in horizontally offset relation with respect to the vertical axis of the first-named pot.

The location of said second pot 7 is furthermore such as to render same readily accessible from the exterior of the furnace through a lateral opening or doorway 8 that is provided with a suitable door 9 by means of which it may be normally closed. Said pot 7, it will be noted, has no cover; whereas, the main pot 5, which otherwise would be open to the atmosphere, is normally kept closed by a heavy

cover 10 securely clamped to the peripheral edge of said pot. This cover 10 carries a rotary paddle or equivalent stirring device 11, the shaft 12 of which projects above the cover and is provided with a crank 13 or equivalent operating means. Said cover also carries a depending tube 14 sealed at its lower end into which a thermometer may be inserted in order to determine the temperature of the molten metal in the pot.

In addition to the foregoing accessories, said cover is provided with a normally closed opening 15 through which small quantities of metal, more particularly of alloying ingredients, may be introduced into the pot, it being understood that for the purpose of introducing into the latter the main charge of metal, the cover 10 will be lifted off. A second opening 16 may also be provided in said cover, as shown, with a weighted cap 17 to serve as a safety vent in the event of the occurrence of an excessive pressure within the pot.

Adjacent its bottom said main pot 5 is formed with a lateral discharge opening 18 that is controlled by a reciprocable valve or stopper 19, the stem 20 of which projects horizontally through the adjacent furnace wall 1. A compression spring 21, coacting with said stem, normally seats valve 19, but by pressing downwardly on a treadle 22, suitably connected with said stem through the medium of a link 23 and bell crank 24, the valve may be opened, as will be readily understood. It will be noted that the lower end of the thermometer receiving tube 14 extends downwardly nearly into the passage 18 and so enables the thermometer therein to register the temperature of the metal as it is actually being discharged from the pot.

A downwardly directed nozzle 25 is attached to the outlet opening 18 on the valve 19, such nozzle being located centrally over the supplemental pot 7 so that the metal will discharge directly into the latter. The upper edge of such supplemental pot 7, it will be noted, lies substantially on a level with the floor or working platform 26 whereon the furnace operator will stand, and the treadle 22 is likewise supported on such floor. Accordingly, molten metal in said pot 7 may be readily dipped out by throwing open door 9 and similarly when it is desired to transfer metal from the main melting pot to the supplemental pot, the mechanism for operating

the discharge valve 19 is conveniently at hand.

Ordinarily it is contemplated that it will not be necessary to employ a fluxing medium over the metal in the main pot 5, but instead an atmosphere of some inert gas, such as sulphur dioxide, will suffice to prevent undue oxidation of the molten charge therein. In the case of the supplemental pot, a coating 10 of flux will desirably be provided, although the gases of combustion that pass around and over said pot will similarly serve as a blanketing medium to prevent undue oxidation of the metal whether it is being transferred 15 from the main pot to the supplemental pot or is being removed from the latter in the fashion above described.

Other modes of applying the principle of my invention may be employed instead of the 20 one explained, change being made as regards the mechanism herein disclosed, provided the means stated by any of the following claims or the equivalent of such stated means be employed.

25 I therefore particularly point out and distinctly claim as my invention:

1. In a metal melting furnace, the com-

bination of a main chamber, a supplemental chamber, a melting pot supported in the upper portion of said main chamber with its 30 top accessible externally of said chamber and having a valve controlled gravity discharge opening, and a second pot supported in said supplemental chamber in position to receive metal discharged from said first pot. 35

2. In a metal melting furnace, the combination of a main chamber, a supplemental chamber connected for the parallel passage therethrough of a portion of the heating gases, a melting pot supported in the upper 40 portion of said main chamber with its top accessible externally of said chamber and having a gravity discharge opening, a valve operable from without said furnace adapted to control such opening, and a second pot 45 supported in said supplemental chamber in position to receive metal discharged from said first pot, said furnace being provided with a door affording access both to the discharge opening of said first pot and to said second 50 pot.

Signed by me this 8th day of January, 1926.

JOHN E. HOY.
